DUST-PAN

Elmer L. Johnson, Chicago, Ill.

Application July 7, 1954, Serial No. 441,779

11 Claims. (Cl. 65—20)

This invention relates to improvements in dust-pans and the like.

The conventional household dust-pan usually has a wide and comparatively thin leading edge so formed as to lie flat on the surface from which dust, dirt, and other particles are to be swept or brushed up for deposit into some kind of a refuse container. Frequently, the leading edge of the pan is of an expanse greater than the mouth of the container. On such occasion the pan has to be tilted so as to shift the accumulations to one side in an attempt to insure their deposit in the narrow-mouthed container. Not infrequently it happens that this may not be done effectively enough to avoid spilling some of the accumulations back onto the floor.

The main objects of this invention are to provide an improved form of dust-pan having means for so reducing the expanse of the leading edge of the pan so as to constitute a converging chute and thereby facilitate emptying the collected accumulations into the desired refuse container; to provide an improved dust-pan of this kind having hingedly connected sections relatively shiftable to each other and the bottom of the pan to constitute the pan from a wide leading edge and outwardly diverging sides to a narrowed leading edge with inwardly converging sides; to provide improved means associated with the dust-pan handle for easily effecting the shifting of the sections between the opposite positions; and to provide an improved dust-pan of this kind which is so simple in construction as to make its manufacture very economical and its use highly commended to those who have need for such a household accessory.

One specific embodiment of this invention is shown in the accompanying drawings, in which:

Figure 1 is a front perspective view of an improved dust-pan constructed in accordance with this invention, the same being shown with the shiftable sections in their respective positions for constituting a dust-pan of more or less conventional appearance;

Fig. 2 is a front perspective of this improved dust-pan showing the shiftable sections positioned to narrow the leading edge and provide converging vertical sides;

Fig. 3 is a rear perspective of the dust-pan as shown in Fig. 1;

Fig. 4 is a view similar to Fig. 1 but indicating the pan as such in dotted or phantom outline and the section-shifting mechanism in full outline;

Fig. 5 is a view similar to Fig. 2 but indicating the pan as such in dotted or phantom outline and the section-shifting mechanism in full outline;

Fig. 6 is a transverse, front-to-rear, fragmentary sectional view of the pan taken on the plane of the line 6—6 of Fig. 1.

Fig. 7 is an enlarged, fragmentary, detail part of the section-shifting mechanism taken on the plane of the line 7—7 of Fig. 6; and

Fig. 8 is an enlarged fragmentary sectional detail taken on the plane of the line 8—8 of Fig. 6.

2

The essential concept of this invention involves a conventional hooded central bottom portion with pairs of sections at each side thereof hinged together in pairs and one of each such pair being hinged along its edge to the central bottom portion, the sections being connected to a trigger-operated rocker-arm-and-link mechanism whereby the sections are shiftable between positions wherein one section of each pair is disposed in the plane of the central bottom portion with the other section of each pair disposed transverse to the central bottom portion and positions wherein the one section of each pair is disposed transverse to the plane of the central bottom portion with the other section of each pair disposed in the plane of the respective one section.

15 An improved dust-pan embodying the foregoing concept comprises a main part A, with hinged and relatively shiftable sections 3, 4, 5 and 6, an overhanging back section formed of the back 13 and hood 7, and handle 8 connected to a back 13, and a section-shifting mechanism B.

The main part A includes the central bottom portion 2 with which is associated the bottom extension sections 3 and 4 hingedly interposed between the central bottom portion 2, and the side sections 5 and 6. The significant feature of this disclosure is the shape and arrangement of the sections so that they may be disposed in alternate positions with respect to the central bottom portion 2.

In one position, the sections 3 and 4 constitute extensions of the central bottom portion 2, so as to present the conventional wide leading edge for the pan, with the side sections 5 and 6 upwardly disposed transverse to the bottom portion 2 and diverging outwardly away from the handle 8, quite like the conventional dust-pan. In their other positions the sections 3 and 4 are disposed transverse to the plane of the central bottom section 2 and the side sections 5 and 6 are disposed in the plane of the sections 3 and 4. So positioned and aligned the sections 3, 4, 5 and 6 converge inwardly away from the handle 8 narrowing the leading edge of the bottom portion 2 and constituting the sort of chute above such bottom portion 2.

The central bottom portion 2 is formed with reinforcing ribs 2a.

45 The sections 3 and 4 are of substantially triangular shape and connected along one edge to opposite edges of the bottom portion 2 by piano hinges 9 and 10 respectively. The other edges of these triangular sections 3 and 4 are connected to the side sections 5 and 6 respectively by other piano hinges 11 and 12.

50 The back 13, normally integral with the bottom portion 2, is inclined upwardly and is here shown formed with flutes 13' at the ends. Adjacent each fluted end 13', on the inner face, is a spring clip 34 which coacts with such fluted ends to provide slots to receive the rear ends of the respective side sections 5 and 6 and guide them in their movement between the position shown in Figs. 1 and 2.

55 The hood 7 is formed with a flange 7' along all but the forward edge, more or less conforming with the contour of the back 13, so as to fit down over the upper edge of the back 13. Screws 14 are used to supplement the friction grip of the hood flange 7' on the back 13 and insure against its accidental displacement.

60 The handle 8 could be formed in several ways. Here it is shown bent to desired form from a specially shaped piece of sheet metal. It has an inward taper and is here shown secured to the back 13 by a bolt and nut 15 and a reinforcing plate 21. Such a handle might be secured to the back 13 in other ways, as for example, by welding.

65 The section-shifting mechanism B includes a pair of

3

rocker arms 24 and 25, mounted on the hood 7, connected by links 30 and 31 to the side sections 5 and 6 and by a link 18 to a trigger 16, the rocker arms being normally urged by springs 37 and 38 to position the sections 3, 4, 5 and 6 as shown in Fig. 1.

The rocker arms 24 and 25 are pivoted on the under side of the hood 7 by the respective screws 35 and 36. These pivots are so positioned that the opposed ends of the rocker arms overlap with the slots 23 therin in registration to receive the extension 22 on the inner end of the link 18.

The links 30 and 31 are pivoted at 32 and 33 to the outer ends of the respective rocker arms 25 and 24 and to angle brackets 28 and 29 secured to the inner faces of the side sections 6 and 5.

The trigger 16 is a channel-shaped piece of metal pivotally secured to the under side of the handle 8, by a screw 17, in position to be conveniently engaged by one or more fingers on the hand grasping the handle 8. At a point above the pivot screw 17, the trigger 16 is formed with an aperture 40 to receive the inner hooked end of the link 18, which is offset at 39 (see Fig. 6) so as to aline the rear portion of the link with and permit its extension through registering apertures 19 and 20 in the back 13 and plate 21.

The springs 37 and 38 are each formed at one end to embrace the link extension 22, as indicated at 41 in Fig. 6, where the extension extends through slots 23 in the overlapping ends of the rocker arms 24 and 25. The other ends of the springs 37 and 38 are anchored to the back 13, as indicated at 42 in Fig. 6. These springs 37 and 38 are tensioned so that they normally actuate the rocker arms 24 and 25 to dispose the sections 3, 4, 5 and 6 in the relative positions shown in Fig. 1.

This improved dust-pan is used in the following manner:

Normally, under the urging of the springs 37 and 38, the rocker arms 24 and 25, through the action of the links 30 and 31, hold the sections 3, 4, 5 and 6 in the relative positions shown in Fig. 1. As is clear from the figure, this is a more or less conventionally shaped dustpan, and is used in the conventional manner.

Once dust, dirt, and/or other particles have been collected on the pan, the trigger 16 is pulled upwardly. This causes the link 18 to swing the rocker arms 24 and 25, against the action of the springs 37 and 38, from the position shown in Fig. 4 to that shown in Fig. 5. Such swinging of the rocker arms 24 and 25 causes the links 30 and 31 to pull on the side sections 5 and 6 inwardly which shifts the sections 3 and 4 up into vertical positions transverse to the central bottom portion 2, with the side sections 5 and 6 disposed above and in the plane of the triangular bottom sections 3 and 4.

Any accumulations on the sections 3 and 4 will be shifted over onto the bottom portion 2 and the inwardly converging sections 3, 4, 5 and 6 narrow the leading edge of the central bottom portion 2 and provide a kind of chute which facilitates the transference of the pan's accumulations to a refuse receptacle, and especially one with a smaller opening than the normal wide leading edge of the conventional dust-pan.

Although but one specific embodiment of this invention is herein shown and described, it will be understood that numerous details of the structure shown may be altered or omitted without departing from the spirit of the invention as defined by the following claims.

I claim:

1. A dust-pan comprising, a central bottom portion, a pair of sections at each side of the central bottom portion hinged to each other with one section of each pair hinged to the central bottom portion a handle extending rearwardly of said central bottom portion, and manually-operated means on said handle shiftable towards the main axis of said handle for relatively shifting the sections between positions wherein the one section of each

4

pair is disposed in the plane of the central bottom portion with the other section of each pair disposed transverse to the central bottom portion in which position said other sections diverge outwardly with respect of the rear end of the pan and positions wherein both of the sections of each pair are disposed transverse to the plane of the central bottom portion with the other section of each pair disposed in the plane of the respective one section whereby the respective planes of the pairs of sections extend inwardly towards each other in the direction of the forward end of the pan.

2. A dust-pan comprising, a central bottom portion, an upstanding back section along the rear edge of the central bottom portion, a handle secured to said back section and extending rearwardly thereof a pair of sections at each side of the central bottom portion hinged to each other with one section of each pair hinged to the central bottom portion, a hood having one edge secured to the upper edge of said back section with the main portion thereof extending over and spaced from said central bottom portion rocker arm mechanism pivoted on said hood, links connecting the respective other sections of each pair with the rocker arm mechanism, and manually operable means on said handle shiftable towards and from the main axis of said handle for actuating the rocker arm mechanism, for relatively shifting the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section.

3. A dust-pan comprising, a central bottom portion, an upstanding back section along the rear edge of the central bottom portion, a rearwardly extending handle secured to the back section, a pair of sections at each side of the central bottom portion hinged to each other with one section of each pair hinged to the central bottom portion, a hood having one edge secured to the upper edge of said back section with the main portion thereof extending over and spaced from said central bottom portion rocker arm mechanism pivoted on said hood, links connecting the respective other sections of each pair with the rocker arm mechanism, a trigger pivoted on said handle, and a link connecting the trigger to the rocker arm mechanism whereby swinging of the trigger towards and from the main axis of said handle effects a relative shifting of the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section.

4. A dust-pan comprising, a central bottom portion, an upstanding back section along the rear edge of the central bottom portion, a rearwardly extending handle secured to the back section, a pair of sections at each side of the central bottom portion hinged to each other with one section of each pair hinged to the central bottom portion, a hood having one edge secured to the upper edge of said back section with the main portion thereof extending over and spaced from said central bottom portion rocker arm mechanism pivoted on said hood links connecting the respective other sections of each pair with the rocker arm mechanism, a trigger pivoted on the handle and shiftable towards the main axis of said handle, a link connecting the trigger to the rocker arm mechanism whereby the opposite swinging of the trigger effects a relative shifting of the sections between a position wherein the one section of each pair is disposed in the plane of the central bottom portion with the other section of each

pair disposed transverse to the central bottom portion and a position wherein the one section of each pair is disposed transverse to the plane of the central bottom portion with the other section of each pair disposed in the plane of the respective one section, and spring means normally urging said trigger-connected link rearwardly towards said handle to dispose the sections in the first of the above mentioned positions.

5. A dust-pan comprising, a central bottom portion, an upstanding back section along the rear edge of the central bottom portion, a pair of sections at each side of the central bottom portion hinged to each other with one section of each pair hinged to the central bottom portion, a hood having one edge secured to the upper edge of said back section with the main portion thereof extending over and spaced from said central bottom portion rocker arm mechanism pivoted on said hood, links connecting the respective other sections of each pair with the rocker arm mechanism, manually operable means for actuating the rocker arm mechanism, for relatively shifting the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section, and means on the back section forming fingers for receiving the rear ends of the respective other sections for guiding them in their movements between the above-mentioned positions.

6. A dust-pan comprising, a central bottom portion, an upstanding back section along the rear edge of the central bottom portion, a pair of sections at each side of the central bottom portion hinged to each other with one section of each pair hinged to the central bottom portion, a hood having one edge secured to the upper edge of said back section with the main portion thereof extending over and spaced from said central bottom portion rocker arm mechanism pivoted on said hood, links connecting the respective other sections of each pair with the rocker arm mechanism, manually operable means for actuating the rocker arm mechanism, for relatively shifting the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section, and yielding members secured at the opposite ends of the back and coacting therewith to form fingers for receiving the ends of the respective other sections for guiding them in their movements between the above-mentioned positions.

7. A dust-pan comprising, a central bottom portion, an upstanding back section along the rear edge of the central bottom portion, a rearwardly extending handle secured to the back section, a pair of sections at each side of the central bottom portion hinged to each other with one section of each pair of substantially triangular form and hinged along one edge to the central bottom portion, a hood having one edge secured to the upper edge of said back section with the main portion thereof extending over and spaced from said central bottom portion a pair of rocker arms pivoted on said hood, links connecting the respective other sections of each pair with the rocker arms, a trigger pivoted on the handle, and a link connecting the trigger with the pair of rocker arms whereby the opposite swinging of the trigger effects the relative shifting of the sections between a position wherein the one section of each pair is disposed in the plane of the central bottom portion with the other section of each pair disposed transverse to the plane of the central bottom portion with the other section of each pair disposed transverse to the plane of the central bottom portion with the other section of each pair disposed in the plane of the respective one section, and spring means normally urging the trigger-connected link to dispose the sections in the first of the above mentioned positions.

the central bottom portion and a position wherein the one section of each pair is disposed transverse to the plane of the central bottom portion with the other section of each pair disposed in the plane of the respective one section.

8. A dust-pan comprising, a central bottom portion, an upstanding back section along the rear edge of the central bottom portion, a rearwardly extending handle secured to the back section, a pair of sections at each side of the central bottom portion hinged to each other with one section of each pair of substantially triangular form and hinged along one edge to the central bottom portion, a hood having one edge secured to the upper edge of said back section with the main portion thereof extending over and spaced from said central bottom portion a pair of rocker arms pivoted on said hood, links connecting the respective other sections of each pair with the rocker arms, a trigger pivoted on the handle, a link connecting the trigger with the pair of rocker arms whereby the opposite swinging of the trigger effects the relative shifting of the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section, and a spring means normally urging the trigger-connected link to dispose the sections in the first of the above positions.

9. A dust-pan comprising, a central bottom portion, an upstanding back with a forwardly-extending hood arranged along and over the rear part of the central bottom portion, a rearwardly extending handle on the back, a pair of sections at each side of the central bottom portion hinged to each other with one section of each pair of substantially triangular form and hinged along one side to the central bottom section, a pair of rocker arms pivoted on the under side of the hood, links connecting the respective other sections of each pair with the rocker arms, a trigger pivoted on the handle, and a link connecting the trigger with the pair of rocker arms whereby the opposite shifting of the trigger effects the relative shifting of the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section.

10. A dust-pan comprising, a central bottom portion, an upstanding back with a forwardly extending hood arranged along and over the rear part of the central bottom portion, a rearwardly extending handle on the back, a pair of sections at each side of the central bottom portion hinged to each other with one section of each pair of substantially triangular form and hinged along one side to the central bottom portion, a pair of rocker arms pivoted on the under side of the hood, links connecting the respective other sections of each pair with the rocker arms, a trigger pivoted on the handle, a link connecting the trigger with the pair of rocker arms whereby the opposite shifting of the trigger effects the relative shifting of the sections between a position wherein the one section of each pair is disposed in the plane of the central bottom portion with the other section of each pair disposed transverse to the central bottom portion and a position wherein the one section of each pair is disposed transverse to the plane of the central bottom portion with the other section of each pair disposed in the plane of the respective one section, and spring clips secured at the ends of the back to form fingers for receiving the rear ends of the respective other sections for guiding them in their movements between the above-mentioned positions.

them in their movements between the above-mentioned positions.

11. A dust pan comprising a central bottom portion, an upstanding back portion along the rear edge of the central bottom portion, a pair of sections at each side of said bottom portion, hinged to each other with one section of each pair hinged to the central bottom portion, normally one section of each pair is disposed in the plane of the central bottom portion with the other sections of each pair disposed transverse to the central bottom portion, a hood having one edge secured to the upper edge of said back portion with the main portion thereof extending over and spaced from said bottom portion, rocker arm mechanism pivoted on the hood, links connecting the respective other sections of each pair with the rocker arm mechanism, a handle secured

to and extending rearwardly of said back section, manually operable means pivotally secured to said handle and connected to said rocker arms and shiftable towards the main axis of said handle for relatively shifting the sections between the above-mentioned position and a position wherein both sections of each pair are disposed transverse to the plane of the central bottom portion, and spring means normally urging said shiftable means to dispose the sections in the first of the above-mentioned positions.
